His Attorney.

UNITED STATES PATENT OFFICE

2,443,921

COUPLING ARRANGEMENT

William W. Moe, Stratford, Conn., assignor to
General Electric Company, a corporation of
New York

Application November 29, 1943, Serial No. 512,173

2 Claims. (Cl. 178—44)

1

My invention relates to electric transmission systems and, in particular, to an arrangement for coupling different sections of such a system.

An object of my invention is to provide an improved coupling arrangement for an electric transmission system.

Another object of my invention is to provide a new and improved means for coupling a cavity resonator to a concentric transmission line.

A further object of my invention is to provide a new and improved arrangement for coupling a cavity resonator to a concentric transmission line in which adjustments of the amount of coupling may be made without removing or disconnecting any of the coaxial cables.

Still another object of my invention is to provide a new and improved arrangement for coupling a cavity resonator to an output line in which adjustment of the coupling may be made while the equipment is in operation.

A still further object of my invention is to provide a new and improved high frequency coupling arrangement in which dielectric losses are reduced to a minimum.

Still another object of my invention is to provide a new and improved arrangement for coupling a cavity resonator to an output circuit in which attenuation of unwanted frequencies is provided without attenuation of a desired frequency.

A still further object of my invention is to provide a new and improved coupling arrangement for the high frequency transmission system which is simple in construction, installation, and adjustment.

One of the features of my invention is the use, in conjunction with a cavity resonator, of a stub transmission line short-circuited at one end and having an output circuit connected thereacross intermediate the point of short-circuit and the point of connection with the cavity resonator. A centrally disposed conductor within the stub transmission line has a longitudinal bore in which is supported a metallic rod which extends beyond the end of the conductor into the cavity resonator. Means external of the stub transmission line are provided to adjust the position of the metallic rod within the cavity resonator to effect a desired transfer of electromagnetic energy between the resonator and the output circuit.

The features of my invention which I believe to be novel are set forth with particularity in the appended claims. My invention itself, however, both as to its organization and method of operation, together with further objects and advan-

2

tages thereof, may best be understood by reference to the following description taken in connection with the accompanying drawing in which the single figure illustrates a coupling arrangement constructed in accordance with my invention.

In the drawing, I have shown a space resonant cavity of the concentric or coaxial transmission line type and which comprises a tubular outer conductor 1 and a centrally disposed inner conductor 2. Means for exciting the space resonant cavity are provided and may take the form of an electric discharge device 3 having its anode 4 coupled to the tubular outer conductor 1 and its grid electrode 5 connected to the inner conductor 2. The anode 4 and the grid 5 may be mounted external to the cavity resonator or these electrodes themselves may form a portion of the space resonant system defined in part by the conductors 1 and 2. The frequency of the cavity resonator defined by the conductors 1 and 2 may be adjusted in any well-known manner, for example, by means of a metallic plunger (not shown) which engages the outer wall of conductor 2 and the inner wall of conductor 1 and which is positionable along the longitudinal axis of these conductors.

The outer conductor 1 is provided with a circular aperture 7 and a stub transmission line 8 is mounted on the external surface of tubular outer conductor 1 concentrically with the aperture 7. The stub transmission line 8 comprises a tubular metallic outer conductor 9 and a centrally disposed inner conductor 10. Means for mounting the stub transmission line 8 on the external surface of conductor 1 comprises the bushing member 11 which extends through the aperture 7 and has a flanged head portion 12 which engages the inner surface of conductor 1. The bushing 11 is externally threaded and engages internal threads on the lower portion of tubular conductor 9. A washer 13 having a shape conforming to the outer surface of tubular conductor 1 is interposed between the lower end of conductor 9 and tube 1. The stub transmission line 8 at its upper end is short-circuited by means of a transverse metallic member 14. In actual construction preferably the members 9, 10 and 14 are formed as a unit.

Connected across the stub transmission line 50 at the point 16 between the short-circuit 14 and the opening 7 is an output circuit in the form of a concentric transmission line having a tubular outer conductor 17 and a centrally disposed inner conductor 18. The conductor 17 is connected to outer conductor 9 of the stub transmission line

by means of a short sleeve 19 formed integrally with the outer conductor 9 and conductor 18 may be joined, as by soldering, to a conductor 20 attached to inner conductor 10 of the stub transmission line. The outer conductor 17 and the sleeve 19 may be externally threaded and held together by means of a nut 21.

Electromagnetic energy is transferred between the concentric transmission line 1, 2 and the transmission line 17, 18 by means of a probe which extends into the space between conductors 1 and 2. This probe or electrode is constituted by a plate or disk 22, which is in spaced relation with the outer surface of inner conductor 2, and attached to the lower end of a conductive rod 23 which passes through a longitudinal bore 25 in inner conductor 10. The bore 25 in conductor 10 may be threaded, if desired, and the position of disk 22 with respect to conductor 2 may be adjusted by means of a knurled knob 24 attached to the end of rod 23.

In the coupler arrangement described, the point of connection 16 of the element 23 to conductor 10 is selected so that the distance from the point 16 to the short-circuit 14 is equal to a quarter wave length or an odd multiple thereof of the electromagnetic wave present in the resonant cavity comprising conductors 1 and 2. With this construction, the stub transmission line 9 and 10 appears as a high impedance for currents of the frequency of the electromagnetic wave to be transmitted so that these currents travel over the conductor 23 to the conductor 20 and the concentric transmission line 17, 18. For currents of other frequencies, the stub transmission line 8 between the points 16 and 14 offers less impedance so that this quarter wave length section attenuates unwanted frequencies. In effect, therefore, the stub transmission line 8 functions as a frequency filter preventing passage of unwanted frequencies and offering low attenuation to the transmission of currents of desired frequency between the cavity resonator and transmission line 17, 18.

In the construction, moreover, the ratios of the diameters of the various sections of concentric transmission line, such as the ratio of the diameters of rod 23 and bushing 11, of elements 19 and 20, and of conductors 9 and 10, are made equal to each other and equal to the ratio of the diameters of conductors 17 and 18 and conductors 1 and 2 so that the path of the current flow through the coupler is made to appear as a continuation of the external transmission line 17, 18 having the same surge impedance as the output circuit.

By the construction described, it is seen that the use of insulating materials for supporting conductors and the pick-up probe 22 is avoided and electrical dielectric losses are minimized. Furthermore, since adjustments of the coupler may be made without removing external cables or even moving the stub line 8 or the external line 17, 18, rigid and permanent connections of all these sections of lines may be employed and adjustments of coupling may be effected while the transmission system is in operation.

While I have illustrated a particular embodiment of my invention, it is apparent that certain modifications may be made. Thus, instead of the capacitive coupling constituted by the disk 22, an inductive coupling in the form of a loop

connected between rod 23 and bushing 11 may be employed. Similarly, while I have shown a particular type of cavity resonator, namely, the concentric transmission line 1, 2, any other type of cavity resonator or any means for transmitting electromagnetic energy may be employed, such as a dielectric wave guide of the hollow-pipe type.

It will be understood, therefore, that while I have shown a particular embodiment of my invention, I do not wish to be limited thereto since many modifications may be made and I contemplate by the appended claims to cover any such modifications as fall within the true spirit and scope of my invention.

What I claim as new and desire to secure by Letters Patent of the United States is:

1. A high frequency system comprising a concentric transmission line including inner and outer cylindrical conductors, the outer conductor of said line having an opening therein, a stub concentric line including an outer conductor connected at one end to the outer conductor of said transmission line and surrounding said opening, said stub concentric line including a central conductor conductively connected to the outer conductor of said stub transmission line at the opposite end thereof, a third concentric transmission line including inner and outer conductors conductively connected respectively with the inner and outer conductors of said stub transmission line, the inner conductor of said stub transmission line having an axial bore therein, and an elongated conductor received within said bore and movable with respect thereto and terminating in an enlargement positioned in spaced relation with respect to the inner conductor of the first-mentioned transmission line.

2. A high frequency system comprising a concentric transmission line including inner and outer cylindrical conductors, the outer conductor of said line having an opening therein, a stub concentric line including an outer conductor connected at one end to the outer conductor of said transmission line and surrounding said opening, said stub concentric line including a central conductor conductively connected to the outer conductor of said stub transmission line at the opposite end thereof, a third concentric transmission line including inner and outer conductors conductively connected respectively with the inner and outer conductors of said stub transmission line at a quarter wavelength or odd multiple thereof from the point where the conductors of said stub line are connected together, the inner conductor of said stub transmission line having an axial bore therein, and an elongated conductor received within said bore and movable with respect thereto and terminating in an enlargement positioned in spaced relation with respect to the inner conductor of the first-mentioned transmission line.
